UNITED STATES PATENT OFFICE

124,707

DESIGN FOR A COLLAPSIBLE TUBE HOLDING AND COMPRESSING DEVICE

Leo Baumeister, Chicago, Ill.

Application November 2, 1940, Serial No. 96,264

Term of patent 7 years

To all whom it may concern:

Be it known that I, Leo Baumeister, a citizen of the United States of America and a resident of Chicago, Cook County, Illinois, have invented a new, original, and ornamental Design for a Collapsible Tube Holding and Compressing Device, of which the following is a specification, reference being had to the accompanying drawing, forming a part thereof.

Figure 1 is a front perspective view of the col-

lapsible tube holding and compressing device showing my new design.

Figure 2 is a rear perspective view of the same.
Figure 3 is a top plan view.

I claim:

The ornamental design for a collapsible tube holding and compressing device, substantially as shown,

LEO BAUMEISTER,
